UNITED STATES PATENT OFFICE.

PETER R. WARREN, OF BROOKLINE, MASSACHUSETTS.

PAPER BOX.

No. 821,907.

Specification of Letters Patent.

Patented May 29, 1906.

Application filed August 18, 1905. Serial No. 274,696.

To all whom it may concern:

Be it known that I, PETER R. WARREN, a citizen of the United States, residing at Brookline, county of Norfolk, State of Massachusetts, have invented a certain new and useful Improvement in Paper Boxes, of which the following is a specification, reference being had therein to the accompanying drawings.

10 My invention has for its object to provide an improved folding box of the kind in which one end folds over two end wings and forms a double bottom for the box. The box embodying my invention may be used either with or without a "tube," and it may also be employed as a cover for a box.

20 My invention has for its object to provide means for preventing the double bottom from becoming displaced, so that articles contained within the box shall not have any opportunity of getting under the bottom of the box and also so that the box may not be weakened by the lifting up of this double bottom.

25 My invention has also for its object to provide a box which may be pulled out of the tube in which it is placed or from under a pile of boxes without the parts becoming displaced even when it is filled with heavy articles. A box embodying my invention is 30 very strong and not likely to become knocked down.

35 My invention will be fully understood from the following description, taken in connection with the accompanying drawings, and the novel features thereof will be pointed out and clearly defined in the claims at the close of this specification.

40 In the drawings, Figure 1 is a plan view of the blank suitable to be folded up to form the box embodying my invention. Fig. 2 is a view, on a somewhat enlarged scale, of the box just before the bottom is pressed into place. Fig. 3 is a tube for the reception of the box. Fig. 4 is a view in perspective of the right-hand end of the box seen in Fig. 2 before the parts are folded into position and shows in addition the modified form of locking means. Fig. 5 is a similar view of the opposite end of the box. Fig. 6 is a perspective view, partly 50 in section, of one end of the box and shows the bottom and locking means in their final position.

55 In the drawings, referring first to Fig. 1, A indicates the bottom of the box, B B the sides of the box, and C C the ends of the box. Attached to the sides B are end wings D,

which fold inwardly, as shown in Figs. 4 and 5, when the sides B are folded into their upright position. Attached to one end piece C is the inner end piece E and the double bottom F, which corresponds substantially in size to the bottom A. To the other end piece C of the box is attached a corresponding inner end piece E, to which in turn are attached the locking means, which I have shown herein as consisting of a tongue or tuck G, located between two projecting portions H and I. This lock may be made in any convenient form—as, for instance, in the shape of a single locking-tongue died out of the bottom locking-piece J. (See Fig. 4.) The various portions of the box-blank described in Fig. 1 are bent along the proper lines, and any convenient means—as, for instance, creasing or scoring—may be employed to facilitate this bending.

55 In making up the box the sides B are first bent to a vertical position and the end wings D are turned inwardly until they assume the positions shown in Figs. 4 and 5. After this the ends C C are folded against the end wings D and the edge K of the double bottom F inserted under the lock G, after which the double bottom F is sprung down into position. It will thus be seen that when this is done the end C and inner end piece E lie against the two sides of the end wings D, holding the said end wings firmly between them. The double bottom F lies closely against the bottom A, except at the right-hand end of the box, 90 where the same is slightly lifted up by the interposition of the side pieces H and I.

95 The double bottom F is held firmly in place by the locking-tongue and by the reverse bend given it when it is placed in position, so that there is no possibility of its springing up and allowing the articles placed in the box to work underneath the bottom when the box is pulled out of the tube (see Fig. 3) by taking hold of the end of the box, as has been the case with boxes of this kind heretofore made.

100 To provide further security against the parts becoming displaced and in order that a person who desires to remove the box from the box in which it is placed, I form thumb-pulls L on each end of the box by cutting them as shown in Figs. 2, 4, 5, and 6. These thumb-pulls have a tendency to bend down slightly when the box is in its folded position, as seen in Fig. 6, and are thus easy to take

hold of when it is desired to pull out the box. This tongue being attached to the bottom A of the box applies the pull directly to the bottom of the box and does not operate to disturb the position of the various members forming the box.

What I claim is—

1. A folding paper box having bottom, side and end portions, one of the end-forming portions having an extension which is folded to form a false inner bottom for the box, the opposite end-forming portion having an extension which forms a double end, and a further extension which rests on the bottom and is slitted back from the end to form a tongue between which and the body of said slitted extension the end of said false bottom is received.

2. A folding paper box comprising a bottom portion, side-forming flaps and end-forming flaps, an extension of one end of said bottom portion forming a double end, and a false bottom, the opposite end of said bottom portion having an extension which forms a double end, and a further extension which is slitted back from the end to form a tongue

between which and the body of said slitted extension the end of said false bottom is received.

3. A folding paper box formed of a single blank, having a bottom portion, two wings which form the sides, each side wing having flaps which turn inward to form ends, the bottom having at one end an extension which folds up over the outer side and down on the inner side of the end-forming flaps of the side wings, and a further extension which forms a false inner bottom for said box, the opposite end of said bottom portion having an extension which folds up on the outer side and down in the inner side of the end-forming flaps of the side wings, and a further extension which is slitted to form a tongue between which and the body of said extension the end of said false bottom is received. 45

In testimony whereof I affix my signature in presence of two witnesses.

PETER R. WARREN.
